(57) **CLAIM**

I claim the ornamental design for a solar cell backing plate, as shown and described.

DESCRIPTION

FIG. 1 is a perspective view of a solar cell backing plate, showing my new design with one solar cell exploded away for clarity of illustration;

FIG. 2 is a front elevational view of FIG. 1, illustrated with the solar cells omitted;

FIG. 3 is a rear elevational view of FIG. 2;

FIG. 4 is a top plan view of FIG. 2, the bottom plan view being a mirror image thereof, and;

FIG. 5 is a left-side elevational view of FIG. 2, the right-side elevational view being a mirror image thereof.

FIG. 6 is a perspective view of an alternate embodiment thereof, illustrated with a plurality of solar cells mounted thereto, one solar cell exploded away for clarity of illustration;

FIG. 7 is a front elevational view of FIG. 6, illustrated with the solar cells omitted;

FIG. 8 is a rear elevational view of FIG. 7;

FIG. 9 is a top plan view of FIG. 7, the bottom plan view being a mirror image thereof, and;

FIG. 10 is a left-side elevational view of FIG. 7, the right-side elevational view being a mirror image thereof. The broken lines showing a plurality of solar cells in FIGS. 1 and 6 depict environmental matter and form no part of the claimed design. The dash-dot broken lines define the bounds of the claim and form no part of the claimed design. The portions of the backing plate shown outside of the dash-dot boundary lines form no part of the claimed design. The remaining broken lines represent stitching, and are part of the claimed design.

1 Claim, 6 Drawing Sheets
